(57) **CLAIM**

The ornamental design for a boom box-shaped on-premises electronic pager, as shown and described.

DESCRIPTION

FIG. 1 is a front perspective view of a boom box-shaped on-premises electronic pager in accordance with the invention;

FIG. 2 is a front view of a boom box-shaped on-premises electronic pager;

FIG. 3 is a rear view of a boom box-shaped on-premises electronic pager;

FIG. 4 is a top view of a boom box-shaped on-premises electronic pager;

FIG. 5 is a bottom view of a boom box-shaped on-premises electronic pager;

FIG. 6 is a left side view of a boom box-shaped on-premises electronic pager; and,

FIG. 7 is a right side view of a boom box-shaped on-premises electronic pager.

The broken lines are for illustrative purpose only and form no part of the claimed design.
